(57) **CLAIM**

The ornamental design for a taillight for a vehicle, as shown and described.

DESCRIPTION

FIG. 1 is a front view of a taillight for a vehicle showing our new design;

FIG. 2 is an enlarged view of the called out portion of FIG. 1;

FIG. 3 is a front and right side perspective view thereof; FIG. 4 is an enlarged view of the called out portion of FIG. 3;

FIG. 5 is a right side view thereof;

FIG. 6 is an enlarged view of the called out portion of FIG. 5;

FIG. 7 is a top view thereof; and,

FIG. 8 is an enlarged view of the called out portion of FIG. 7.

The broken lines shown in the drawings represent a boundary and form no part of the claimed design, with the rest of the vehicle shown in de-emphasized, reduced tonal value so as to illustrate environmental structure. The elements shown outside the broken lines form no part of the claimed design and are merely included to show environmental aspects thereof.
